UNITED STATES PATENT OFFICE.

WILLIAM H. SARGENT, OF ST. LOUIS, MISSOURI, ASSIGNOR TO WAYNE MANUFACTURING COMPANY, OF ST. LOUIS, MISSOURI, A CORPORATION.

WASHING-MACHINE.

1,350,116.

Specification of Letters Patent. Patented Aug. 17, 1920.

Application filed October 17, 1919. Serial No. 331,412.

To all whom it may concern:

Be it known that I, WILLIAM H. SARGENT, a citizen of the United States, residing in the city of St. Louis and State of Missouri, have 5 invented new and useful Improvements in Washing-Machines, of which the following is a specification.

This invention relates to a power-driven washing machine of the rocker type, and in 10 its preferred embodiment, contemplates a construction and arrangement of parts adapting the machine to be operated by an electric motor. Other suitable driving power, however, such as a hydraulic motor, 15 could equally well be employed for this purpose. The invention has for its objects to provide a novel construction and arrangement of parts for insuring a uniform and even rocking movement of the tub; to provide 20 means for preventing the actuating mechanism from stopping on a dead center, and to mount the tub in such a manner that the danger of injury to the operator by having the hand caught in any part of the 25 mechanism, or between the tub and a fixed part of the machine is practically obviated.

In addition to the above specific objects of the invention, other objects reside in the simplicity of the construction involved and 30 the advantages derived from the general construction of the machine as a whole, all of which will more clearly appear from the description to follow:

In the accompanying drawings, 35 Figure 1 is a side elevation of a machine constructed according to my invention with the casing broken away to illustrate the motor drive;

Fig. 2 is a broken longitudinal sectional view of the same;

Fig. 3 is a plan view of the casing and the operating mechanism mounted therein, the tub being removed; and

Fig. 4 is a central vertical section taken 45 on the line 4—4 of Fig. 2.

Referring now to these drawings, the numeral 1 indicates a casing closed on all sides, preferably of metal and rectangular in shape, supported by legs 2 and having an 50 elevated bottom 3, on which, near one end of the casing, is mounted a motor 4, the shaft of which is provided with a drive pulley 5. The driving mechanism includes a cross-shaft 6 suitably mounted within the casing 55 1, which has secured thereon, at one end,

a pulley 7 over which, and the pulley 5, passes a belt 8, by means of which the shaft 6 is driven. On the opposite end of the shaft 6 is secured pinion 9 which meshes with a gear-wheel 10 mounted on one end 60 of a shaft 11, which is parallel with shaft 6. The shafts 6 and 11 are mounted in brackets 12 (Fig. 2) supported on the bottom 3, near opposite sides of the casing 1. The shaft 11 has loosely mounted on its end, remote 65 from the gear-wheel 10, a sleeve carrying a crank arm 13, which is pivotally connected at its outer end to the lower end of a pitman rod 14 as indicated at 15. The upper end of the pitman rod 14 is pivotally connected 70 at 16 to a lug 17, on one end of a rocker frame 18. The sleeve is provided with a fixed clutch member 19, and the shaft with a movable clutch member 20, which is splined on said shaft, and a throw-lever 21 is provided 75 for operating the movable clutch member. This clutch mechanism is of the usual, or any preferred construction, as common in machines of this character, and is illustrated merely for the purpose of making the operation of the machine clear. The rocker frame 18, previously alluded to, comprises two parallel members, each of which is formed preferably of a metal bar bent to provide a rocker 22 (Fig. 2) and a longitudinal member 23 located above the rocker, the two members 23 forming a bed or tub-holder for supporting the bottom 24 of the tub 25. The bars 23 have upwardly turned 80 integral extensions to engage the ends of the tub and the rockers 22 in each instance, preferably unite and are jointly curved upwardly at their opposite ends, as indicated at 26 in Fig. 2, to provide a support and holder for the rounded corners 27 of the tub. The 85 tub 25 is provided at its ends and either side, with suitable means which may be in the form of continuous flanges 28 which embrace the outer sides of the rocker frame 18 to prevent lateral movement of the tub in 90 the frame.

From the construction described, it will be seen that the tub when set in the rocker frame 18, will be held in position therein by means of the curved projections 26 at the 95 ends of the rocker frame and by the flanges 28 embracing the opposite sides of the rocker frame, without any other means of holding the tub in place being required. The construction permits the tub to be readily 100 105 110

placed in position in the rocker frame and as readily removed at all times by simply lifting the tub off the tub holder. The two members of the rocker frame are connected 5 at their opposite ends by cross-bars 29, on one of which the lug 17, previously referred to, is mounted. I provide suitable means for preventing the rocker frame from creeping along the supporting ledges, preferably constructed as follows:—Projecting downwardly from each of the longitudinal members 23 of the rocker frame is a bracket arm 30, (Figs. 2 and 4), the lower ends of these bracket arms being connected by a cross-bar 10 15 31. The numeral 32 indicates two parallel pivot bars which are pivotally mounted at their outer ends at one end of the casing 1, as indicated at 33 in Figs. 2 and 3, and at their inner ends are pivotally mounted on 20 the cross-bar 31. Extending longitudinally of casing 1, near opposite sides thereof, are two parallel angle bars 34 which serve, respectively, as the ledges or supports for the rockers 22, and on which the curved lower 25 edges of said rockers rest and roll, in the operation of the machine. The side flanges 35 of these bars embrace the outer sides of the rockers 22 and thus serve to prevent lateral movement of the rocker frame 18 in the 30 35 operation of the machine.

The operation of the machine is as follows:

The current being turned on to the motor 4, the shaft 6 will be rotated and through 35 the pinion 9 and gear 10, rotate the shaft 11, and the movable clutch member 20; by moving the throw lever 21 this clutch member is thrown into engagement with the fixed clutch member 19, and thereby the crank 40 arm 13 will be caused to be rotated and reciprocate the pitman 14, which movement of the pitman will impart a rocking movement to the tub 25; the latter will be held to a central position on the angle bars 34 by 45 means of the pivot rods 32 engaging the cross-bar 31. There will be a slight sliding movement of the rockers 22 on these angle bars, but in actual practice with a full-size machine, such sliding movement scarcely exceeds one-sixteenth of an inch in extent, and 50 does not affect the even rocking movement of the tub.

Heretofore, it has been attempted to secure the tub in position in its rocking movement by means of a pin and double slot connection, and I originally employed such a construction. It was found, however, that such an arrangement was not feasible, as the movement, or throw of the water and the 55 clothes in the tub was with such force as to cause an end-wise movement of the tub and thus destroy the correct alinement of the pin in the slot, causing the tub to jump at the end of each rocking movement and producing 60 65 70 75 80 85 90 95 100 105 110 115 120 125 130 a great deal of vibration and noise.

These objections are overcome in the present construction by the pivot bars 32, which permit of a free rocking movement of the tub in either direction and at the same time securely hold the tub in its central position on 70 the angle bars 34. Moreover, the said pivot bars being connected to the casing of the machine at their outer ends, can only yield in the upward or downward direction, and hence the tub is forced to rock upon a relatively fixed pivot, with no possibility of being misplaced in movement, and hence vibration and noise are reduced to the minimum.

One of the objects of the invention has 80 been stated to be the prevention of the operating mechanism stopping on a dead center. This object is accomplished through the medium of a coil-spring 36, which is connected at one end to the cross-bar 31 and 85 at the other end to the pitman rod 14, about mid-way of the length of the latter, as shown in Figs. 2 and 3. This spring will operate to pull the pitman rod 14 to the position shown in Fig. 2 whenever the power is 90 turned off, in which position the pivot 15 is out of the line of thrust, as will be seen.

The final object of the invention is concerned with preventing injury to the hand of the operator, and relates to the provision 95 of means for effectively guarding the driving mechanism, at the same time providing a construction rendering the motor and driving mechanism readily accessible. This object is effected by inserting the tub 25 100 through an opening 37 in the top of the casing 1, and positioning the angle bars 34 well below the top of the casing, so that the rocker frame, as a whole, is below the top of said casing, and the mechanism of the machine is below the tub in the casing and 105 guarded on all sides by the casing. It is impossible, therefore, for the operator or a child to get fingers caught beneath the rocker and the fixed part of the casing or to come 110 into contact with any of the driving parts, and there is no part of the tub which approaches sufficiently close to the edge of the opening 37 to cause injury to the hand of the operator, even should it be inserted in the 115 said opening. But the starting lever is accessible through the opening and access may be readily had to the mechanism through the top opening 37 by removing the tub and the holder.

I claim:

1. A washing machine comprising a casing, having an opening in its top and provided on its interior, and below the top, with rocker supports, a rocker-frame comprising 125 rockers mounted on said supports and a tub holder, a tub insertible through said opening and adapted to be received by said holder, said rocker-frame, when in position on said supports, being located below the 130

top of said casing, and means for rocking said rocker-frame.

2. A washing machine comprising a casing having an opening in its top, and provided on its interior, below the top, with supporting ledges, a rocker-frame comprising rockers with their lower edges resting on said ledges, a tub holder supported on the rockers, a removable tub insertible 10 through said opening and resting in said holder, said rocker-frame, when in position on said ledges, being located below the top of said casing, a motor mounted within the casing below said rocker-frame, and means 15 for rocking said rocker-frame from said motor.

3. A washing machine comprising a casing having an opening in its top and provided on its interior, below the top with 20 supporting ledges, a rocker-frame comprising a tub holder and rockers mounted to roll on said ledges, a tub insertible through said opening and adapted to be received in said holder, bars pivotally mounted at 25 their outer ends, near one end of said casing and at their inner ends being pivotally connected centrally of said rocker-frame, and means for rocking said rocker-frame and tub.

4. A washing machine comprising a casing having an opening in its top and provided on its interior, below the top, with rocker supports, a rocker-frame comprising rockers mounted on said supports and a tub 30 holder, a tub insertible through said opening and adapted to be received by said holder, a cross-bar suspended from the bottom of said tub holder and located centrally thereof, bars pivotally connected at their outer ends 35 near one end of said casing and at their inner ends being pivotally connected to said cross-bar, and means for rocking said rocker-frame and tub.

5. A washing machine comprising a frame 45 having parallel rocker supports mounted therein, a rocker-frame comprising rockers mounted on said supports and a tub holder, bars pivotally connected at their outer ends near one end of said frame, and at their 50 inner ends being pivotally connected to the bottom of said tub holder centrally thereof, and means for rocking said rocker-frame.

6. A washing machine comprising a frame having parallel rocker supports mounted 55 therein, a rocker-frame comprising rockers mounted on said supports and a tub holder, a motor, a crank driven thereby, a pitman connecting said crank and one end of said rocker-frame, and a spring connected to said 60 pitman and operating when the motor is stopped to hold said pitman in a position whereby the said crank will be off of a dead center.

7. A washing machine comprising a frame 65 having rocker supports, a rocker-frame

adapted to receive and hold a tub and having rockers mounted on said supports, a motor, driving mechanism operatively connecting said rocker-frame and motor for rocking the rocker-frame and a tub mounted 70 therein, means for rendering said driving mechanism inoperative, and automatic means for holding the driving mechanism in a position whereby its moving parts will be off of a dead center. 75

8. A washing machine comprising a frame having parallel rocker supports, a rocker-frame mounted on said supports and adapted to receive a tub, a motor, a crank driven by said motor, a pitman connecting said 80 crank and one end of said rocker-frame, means for disconnecting said crank from the motor, and a spring connected at one end to said pitman intermediate the ends thereof and at the other end to a fixed part of the 85 machine, and operating, when the machine is rendered inoperative, to draw said pitman to a position where its connection with the crank will be off of a dead center.

9. A washing machine comprising rocker 90 supports, a rocker-frame mounted on said supports, a tub adapted to be mounted in said rocker-frame, means for maintaining the rocker-frame in a relatively fixed position on said supports comprising a bar pivotally secured at one end to a fixed support and pivotally connected at the other end with said rocker-frame and centrally thereof, and means for rocking said rocker-frame. 95

10. In a washing machine, in combination with parallel angle-bars forming rocker supports, a rocker-frame comprising two connected side members each of which consists of associated metal bars, one of which is curved to form a rocker and the other of which extends longitudinally over the rocker, said bars being connected and jointly curved upward at their ends to form, with said longitudinal portion, a holder, the 100 said holders being adapted to receive and hold a tub, and the said rockers to rest upon and be embraced by said angle bars. 110

11. A washing machine, comprising a casing having an opening in its top, a tub holder supported within the casing and below said opening, a tub resting on said tub holder and removable at will by lifting the same off of the tub holder and through said opening, and means within the casing for 115 rocking the tub holder.

12. In a washing machine, the combination of an elongated casing having an opening through its top, supporting ledges within said casing and below the opening, a tub 120 holder having rockers resting on said ledges, a pitman rod pivotally attached to said tub holder at one end of the tub holder and extending down into the casing, a tub resting on said tub holder and removable at will 125 130

through said opening, a motor within said casing below said tub holder, and means for actuating said pitman rod from said motor.

13. A washing machine comprising a casing having an opening in its top and provided on its interior below the opening with supporting ledges, a rocker frame comprising a tub holder and rockers mounted to roll on said ledges, a tub insertible through said opening and adapted to be received by said holder, means for preventing the rocker frame from creeping along the ledges, and means for rocking said rocker frame and tub.
14. A washing machine comprising a cas-

ing having an opening in its top and provided on its interior below the opening with supporting ledges, a rocker frame comprising a tub holder and rockers mounted to roll on said ledges, a tub insertible through said opening and resting on said tub holder, means for preventing the tub from shifting laterally on the tub holder, means for preventing the rocker frame from creeping along the ledges, and means for rocking said rocker frame and tub.

In testimony whereof I have hereunto set my hand.

WILLIAM H. SARGENT.
